UNITED STATES PATENT OFFICE.

MONTGOMERY H. JOHNSON, OF UTICA, NEW YORK.

IRONING MACHINE.

Application filed April 28, 1922. Serial No. 557,169.

To all whom it may concern:

Be it known that I, MONTGOMERY H. JOHNSON, a citizen of the United States, and a resident of Utica, in the county of Oneida and State of New York, have invented certain new and useful Improvements in Ironing Machines; and I do hereby declare that the following is a full, clear, and exact description thereof, which will enable others skilled in the art to which it appertains to make and use the same, reference being had to the accompanying drawings, and to the reference numerals marked thereon, which form part of this specification.

My present invention relates to an ironing machine.

The purpose of my invention is to provide an ironing machine of new and improved construction and one which is simple in construction and operation and well adapted for domestic use.

A further purpose is to provide a machine of the class described which is moderate in cost, easily operated and controlled by one not an expert in handling machinery and further to provide a machine which is readily adapted for use in the various ways required when ironing many different articles of clothing, bedding or linen.

Another object of my invention is to provide an ironing machine wherein the extent of the stroke of the iron can be readily varied even during operation of the machine in order to readily adapt the machine for operation upon different articles.

Another object is to provide a machine of the class described with a particularly advantageous arrangement for supporting the traveling head carrying the iron, and controlling or varying the extent of the stroke of the iron; a still further purpose is to provide new means for supporting the iron from the traveling head so that the iron may be readily moved to any position cross-wise of the board or to a position off of the board and still further to have said cross-wise adjustment or variation made automatically.

Further purposes and advantages of my invention will appear from the specification and claims herein.

Fig. 1 is a view of a machine embodying my invention said view being mostly in front elevation but with the smoothing iron

and the lazy tongs omitted and with portions of the ironing board cut away in order to show the mechanism more clearly, the parts being so adjusted as to give the traveling head its maximum movement.

Fig. 2 is a top view of the machine on a somewhat larger scale, the handle 47 and trigger therebelow being removed.

Fig. 3 is a vertical sectional view on line 3—3 of Fig. 1 of the back frame and mechanism with an end view of the right hand end frame and ironing board, with the near side of strap 20 broken away.

Fig. 4 is a view similar to Fig. 1 but with the parts adjusted to obtain a reduced amount of reciprocating movement by the traveling head and consequently by the smoothing iron.

Referring to the drawings in a more particular description it will be seen that the machine comprises a back frame 10 having a long upright 11 at its left hand end and an end frame 12 at its right hand end whereby the ironing board 13 and the rest of the machine hereinafter described are held or supported in proper position.

The ironing board 13 is supported at some little distance in front of the back frame 10 and upright 11 and parts attached thereto, by said ironing board having its right hand end attached to or rested upon the forward portion of the end frame 12, and by having its other or left hand end supported by a leg 14.

At the left end of the back frame 10 and in line with the upright 11 there is mounted a pair of guides 15 and 16 respectively, preferably in the form of round rods or tubes held in place by top, intermediate and bottom brackets 17, 18 and 19 respectively, the ends of said brackets encircling said guides and having the central portion or strap securely fastened to the back frame 10 and lower part of the upright 11.

Between the upper ends of the guides 15 and 16 to the center of a strong strap 20 as at 21 is pivotally hung the upper end of the rocker arm 22. The lower end of said arm is pivotally secured to the center of a horizontal cross-bar 23 as at 24. On pivots 25 and 26 respectively extending through said cross-bar at each side of the pivot 24 and in line therewith are pivotally mounted the central points of two parallel supporting bars 27 and 28 respectively which

are twice the length of the rocker arm. The lower ends of said parallel supporting bars 27 and 28 are bent backwardly and pivotally mounted in spaced and horizontal relation to the saddle 29 the opposite sides of which have vertically extending holes therethrough, whereby said saddle is slidingly mounted upon the vertical guides 15 and 16 between the intermediate and lower brackets 18 and 19.

The upper ends of said parallel supporting bars 27 and 28 carry in horizontal position the traveling head 30 as by the upper ends of said bars 27 and 28, being pivotally mounted upon pins 31 and 32 respectively, extending through two pairs of spaced ears 33 and 34 depending from bottom of the head 30.

It will now be seen that a swinging motion given the rocker arm 22 from the position shown in full lines in Fig. 1 to the right will carry the traveling head 30 to the right horizontally and in the same horizontal plane and in substantially a straight line by reason of the saddle 29 sliding downwardly upon the vertical guides 15 and 16 until the parallel rods 27 and 28 come to vertical position and after that by the said saddle again sliding upwardly but with the parallel rods 27 and 28 and the rocker arm 22 to the right of the said vertical guides 15 and 16 until the parts come to the position shown in dotted lines in Fig. 1. It will be obvious also that reversing the rocker arm 22 will again carry the traveling head 30 to the left and if the motion is continued far enough, to the position shown in full lines in Fig. 1 and that at all times the traveling head 30 will be maintained horizontal and in the same horizontal plane.

As means for swinging the rocker arm 22 and thereby giving the said reciprocating movement to the traveling head 30 there is provided upon the rocker arm 22 a crosshead 35 slidingly mounted upon said rocker arm and having projecting to the front as seen in Fig. 1 a pin 37 upon which is pivotally mounted the left hand end of connecting rod 38, the other end of which is mounted upon pin 39 projecting from the wheel or disc 40, mounted upon a part of the frame 10 and suitably driven by means, the detailed description of which is not necessary.

It will now be seen that rotation of the wheel 40 through connecting rod 38 (and assuming the crosshead 35 to be for the time fixed from sliding movement upon the rocker arm 22) will move said rocker arm a given constant amount determined by the distance of the pin 39 from the center of disc 40. In order however, to vary at will the extent of movement of the traveling head 30 and thereby the smoothing iron upon the board I provide the following means for sliding

the crosshead 35 the desired amount upon the rocker arm 22 and holding said crosshead at the desired point along said rocker arm while still allowing free swinging motion of said crosshead 35 and rocker arm 22. A crosshead 41 is slidingly mounted upon the upper halves of the guides 15 and 16 as by said crosshead having in its opposite sides vertically extending apertures slidingly fitting said guides. Upon the top of said crosshead 41 there is provided an upwardly extending ear 42 from which there projects forwardly the pin 43 upon which is pivotally mounted the upper end of the governing arm 44, the lower or free end of which is pivotally connected to the crosshead 35 as at 45. The crosshead 41 is secured to the bottom of a stiff upright bar 46 slidingly mounted at the front of the upright 11. The upper end of bar 46 is provided with a forwardly projecting handle 47 for manual operation of the crosshead 41 up or down upon the guides. The crosshead is held at desired position by means of a trigger 48 mounted in the bar 46 just below the handle 47, engaging any one of a series of suitable holes or notches provided in the upright 11. The forwardly projecting handle 49 of the trigger 48 provides means for releasing the trigger and allowing the crosshead 41 to move. A spring 50 between the trigger handle 49 and the main handle 47 yieldingly hold the trigger 48 in the notch where it had been placed, the upper part of said spring being housed in a socket extending up into said main handle from below and said main handle being recessed below to receive said trigger handle 49.

As the parts are seen in Fig. 1 the crosshead 41 is raised to its upper position bringing the pin 43 at the upper end of the governing arm 44 immediately back of the pin 21 upon which is mounted the upper end of the rocker arm 22. This position gives the maximum amount of reciprocating movement to the traveling head 30. As the crosshead 41 is lowered the governing arm 44 thereby carries the crosshead 35 further down upon the rocker arm 22. While the crosshead 35 is still given the same extent of swinging motion from the connecting rod 38, the lower end of said rocker arm 22 will be given a swinging motion of less extent than before as appears in Fig. 4 and this limitation of movement will in turn be imposed upon the parallel bars 27 and 28 and the traveling head 30 as will appear from Fig. 4. It will be particularly noticed that the means here provided for varying the extent of travel of the head 30 are readily manipulated during operation of the machine and that the machine will not have to be stopped in order to adjust the stroke of the iron to the desired extent of travel.

Towards one end say the right hand end of

the traveling head 30 upon fixed pin 66 is pivotally mounted the inner end of arm 67 of a lazy-tong device 68. The outer ends of the arms of this device are attached to the bar 69 which is secured to the smoothing iron 70. In order that this lazy-tongs device 68 may support the iron 70 adjustably over the board, that is to any position crosswise of the board or even to a point off of the board 50 preferably to the rear of the board, the arm 51 opposite the arm 67 has its inner end, that is the end opposite pin 66, provided with a downwardly extending finger 52, which can slide through slot 53 extending longitudinally of the left hand half of the head 30. The end of the outer arm 54 of the lazy-tongs device connected to the smoothing-iron bar 69 is pivotally mounted upon a fixed pin 55, while the outer end of the opposite arm 56 has a down turned finger 57 which slides in slot 58 extending longitudinally of the left hand portion of the smoothing iron bar 69. It will now be seen that by the operator grasping the handle 59 of the smoothing iron 50 the lazy-tongs 68 may be extended or contracted to any extent within its range of motion so that the iron will travel longitudinally of the ironing board 13 in any position crosswise of the board or if desired off of the board, preferably to the rear, so that clothes may be placed on the board without interference from the iron. The operator by her hand upon the handle 59 of the iron 55 will guide the iron in any desired path upon the board as the machine moves the iron lengthwise thereof.

In order however, to provide for automatically advancing the iron across the board there is provided in both the forward and rear sides of the slots 53 in the traveling head 30 a series of teeth 61 having their left hand sides 62 straight, that is at right angles to the length of the slot and with the right hand sides 63 of the teeth on a slant of an appreciable angle. The teeth on opposite sides of the slot 53 are in staggered position. As the traveling head 30 moves to the right the weight and resistance of the iron at the outer or forward end of the lazy-tongs will cause the finger 52 to engage the rear side of slot 53 and travel down the slanting side 63 of one of the teeth until the straight side 62 of the tooth next to the right is reached. As the head 30 starts its movement to the left 55 the weight and resistance of the smoothing iron will swing the lazy-tongs on pin 66 enough so that finger 52 will be moved to the front side of the slot 53 and said finger will slide down the slanting side 63 of the tooth 60 opposite the straight side 62 of the rear tooth. Each of these movements will extend the lazy-tongs slightly and carry the iron a short distance farther front at the beginning of each motion of the iron. The straight side 65 62 of the succeeding tooth however, will in

each case prevent further extension of the lazy-tongs. As the next movement to the right by the head 30 begins, the finger 52 will be moved to the slanting side of the tooth next to the right of the one theretofore engaged by the finger at the rear of the slot and the finger will move a slight distance to the right as before described. Successive movements of the head will thus move the iron 70 farther front step by step.

This automatic crosswise movement of the iron however, may be readily overcome by the operator pushing or pulling the iron a little so as to disengage the finger 52 from the teeth 61 whereupon the said finger may 80 slide freely lengthwise of the slot 53 and allow the lazy-tongs to be extended or contracted if desired. It will be noted particularly that the iron may be at any time easily shoved rearwardly as far as desired even to 85 the position to the rear of the board since in so contracting the lazy-tongs the finger 52 simply rides by the teeth on either side of the slot 53. Such rearward movement of the iron allows for removing the ironed article 90 and placing another article on the board when the machine will again advance the iron across the board.

Ordinarily the machine will have its drive wheel 40 operated by an electric motor 64 95 which will be started or stopped by a rheostat pedal 65 which can be moved to several positions in the usual well-known manner to obtain different speeds of the motor and so control at will the speed of the traveling of 100 head 30 and the smoothing iron.

What I claim as new and desire to secure by Letters Patent is:

1. In an ironing machine the combination of an ironing board, a head spaced from 105 said board and movable back and forth parallel thereto, a smoothing iron and means extending from said traveling head and carrying said iron over the board and imparting the motion of said head to the iron the said iron-carrying means being adjustable in length during operation of the machine whereby the iron may be made to travel lengthwise of the board in any position crosswise of the board, and means automatically adjusting said carrying means to successively carry the iron at different positions crosswise of the board.

2. In an ironing machine the combination of an ironing board, a head spaced from said board and movable back and forth parallel thereto, a smoothing iron and means including a lazy tongs extending from said traveling head and carrying said iron over the board and imparting the motion of said head to the iron, the said iron-carrying means being adjustable in length during operation of the machine whereby the iron may be made to travel lengthwise of the board in any position crosswise of the board,

- and means automatically adjusting said lazy tongs to successively carry the iron at different positions crosswise of the board.
3. In an ironing machine the combination of an ironing board; a head spaced therefrom and movable back and forth parallel thereto, a smoothing iron and a lazy tongs mounted on said traveling head and supporting said iron over the board and imparting the motion of said head to said iron and means including a step by step escapement device for automatically adjusting said lazy tongs to successive positions.
4. In an ironing machine the combination of an ironing board, a head spaced therefrom and movable back and forth parallel thereto, a smoothing iron and a lazy tongs mounted on said traveling head and supporting said iron over the board and imparting the motion of said head to said iron, and means including two oppositely arranged spaced racks engaging the movable arm of the lazy tongs for automatically adjusting the lazy tongs to successive positions.
5. In an ironing machine, the combination of an ironing board, a head spaced therefrom and movable back and forth parallel thereto, a smoothing iron and a lazy tongs mounted on said traveling head and supporting said iron over the board and imparting the motion of said head to said iron, and means including two oppositely arranged spaced racks having one face of each tooth slanting, the teeth on said racks being in a staggered position, whereby back and forth movement of the head automatically adjusts said lazy tongs to successive positions.
6. In an ironing machine, the combination of an ironing board a head spaced therefrom and movable back and forth parallel thereto, a smoothing iron and a lazy tongs mounted on said traveling head and supporting said iron over the board and imparting the motion of said head to said iron and means including two oppositely arranged spaced racks having one face of each tooth slanting to the same end of the racks, the teeth on said racks being in a staggered position, whereby back and forth movement of the head automatically adjusts said lazy tongs to successive positions.
7. In an ironing machine the combination of an ironing board, a head spaced therefrom and movable back and forth parallel thereto, a smoothing iron and a lazy-tongs mounted on said traveling head and supporting said iron over the board and imparting the motion of said head to said iron and means for automatically adjusting said lazy-tongs to successive positions.
8. In an ironing machine, the combination of an ironing board, a frame having vertical guides, a rocker arm having its
- upper end pivoted to said frame above the guides, means for imparting a swinging motion to said rocker arm, a pair of parallel supporting bars pivotally supported midway their length by the lower end of said rocker arm and slidingly mounted at their lower ends upon said guides, a head horizontally supported by the upper ends of said parallel bars and moved thereby parallel to the ironing board and a smoothing iron carried by said head over and longitudinally of the ironing board.
9. In an ironing machine, the combination of an ironing board, a frame having vertical guides, a rocker arm having its upper end pivoted to said frame above the guides, means for imparting a swinging motion of adjustable extent to said rocker arm, a pair of parallel supporting bars pivotally supported midway their length by the lower end of said rocker arm and slidingly mounted at their lower ends upon said guides, a head horizontally supported by the upper ends of said parallel bars and moved thereby parallel to the ironing board, and a smoothing iron carried by said head over and longitudinally of the ironing board.
10. In an ironing machine, the combination of an ironing board, a frame having vertical guides, a rocker arm having its upper end pivoted to said frame above the guides, means for imparting a swinging motion to said rocker arm, a pair of parallel supporting bars pivotally supported midway their length by the lower end of said rocker arm and slidingly mounted at their lower ends upon said guides, a head horizontally supported by the upper ends of said parallel bars and moved thereby parallel to the ironing board, a smoothing iron carried by said head over and longitudinally of the ironing board.
11. In an ironing machine the combination of an ironing board, a head spaced therefrom and movable back and forth parallel thereto, a smoothing iron and a lazy-tongs mounted on said traveling head and supporting said iron over the board and imparting the motion of said head to said iron and means including a toothed slot in said head engaging the movable arm of the lazy-tongs for automatically adjusting said lazy-tongs to successive positions.
12. In an ironing machine, the combination of an ironing board, a frame having vertical guides, a rocker arm having its upper end pivoted to said frame above said guides, a cross head slidingly mounted on said rocker arm, a pair of parallel supporting bars pivotally supported midway their

- length by the lower end of said rocker arm and slidingly mounted at their lower ends upon said guide bars, a head horizontally supported by the upper ends of said parallel bars and moved thereby parallel to the ironing board, a smoothing iron carried by said head over and longitudinally of the ironing board, means connected to said cross head for imparting a uniform swinging motion to said cross head and means for adjusting said cross head to various positions on said rocker arm whereby the extent of swinging motion imparted to the parallel bars and smoothing iron may be varied.
- 5 13. In an ironing machine, the combination of an ironing board, a frame having vertical guides, a rocker arm having its upper end pivoted to said frame above said guides, a cross head slidingly mounted on
- 10 said rocker arm, a pair of parallel supporting bars pivotally supported midway their
- length by the lower end of said rocker arm and slidingly mounted at their lower ends upon said guide bars, a head horizontally supported by the upper ends of said parallel bars and moved thereby parallel to the ironing board, a smoothing iron carried by said head over and longitudinally of the ironing board, a cross head slidingly mounted on said vertical guides, a control arm 25 pivotally attached at its lower end to the cross head on the rocker arm and at its upper end to cross head on the vertical guides and means for adjusting said cross head on the guides to various positions 30 thereon, whereby the extent of swinging motion imparted to the parallel bars and smoothing iron may be varied.
- 15 13. In an ironing machine, the combination of an ironing board, a frame having vertical guides, a rocker arm having its upper end pivoted to said frame above said guides, a cross head slidingly mounted on
- 20 said rocker arm, a pair of parallel supporting bars pivotally supported midway their

In witness whereof I have affixed my signature, this 18th day of April 1922.

MONTGOMERY H. JOHNSON.
